UNITED STATES PATENT OFFICE.

WILLIAM PENTE, OF CHICAGO, ILLINOIS.

TOY HOUSE.

1,263,282.

Specification of Letters Patent. Patented Apr. 16, 1918.

Application filed June 7, 1915. Serial No. 32,481.

To all whom it may concern:

Be it known that I, WILLIAM PENTE, a citizen of the United States, residing at Chicago, in the county of Cook and State of Illinois, have invented a certain new and useful Improvement in Toy Houses, of which the following is a full, clear, concise, and exact description, reference being had to the accompanying drawings, forming a 10 part of this specification.

Although the invention deals with a toy, the basis of the invention is a scheme of advertising, and the toy house is merely a vehicle for conveying the idea and for rendering it workable.

According to my invention, advertising matter which ordinarily could not be conveyed to nor understood by the child, is rendered particularly valuable and forceful 15 not only to the child but to the elders as well.

I provide a toy house, or play house, which may take the form of a store—in the particular embodiment which I am illustrating I choose to employ a grocery store.

The walls of the store on the outside are lithographed to represent store windows with glass in front and with articles of merchandise displayed therein. The representation is made as tasteful and decorative as possible, with an eye not only to making the same appear artistic, but with a view to forming an accurate and pleasing vehicle for conveying advertising matter. The various articles in the "windows" are so labeled and placed as to give the appearance of the genuine articles which they are to advertise.

To the child this is strikingly attractive, 40 as it gives him a "store front" that appears to contain the very articles which can be seen at the grocery or delicatessen shop.

The interior of the house is provided with lithographed representations of various articles just as they appear in the package, or as the packages themselves appear. A number of shelves are provided, and on the wall back of the same are provided images of articles which appear to be the articles 50 themselves. The intention, however, is that the child shall obtain the package which the lithographed picture represents, and place it upon the shelf in front of the picture. This causes the child to ask its elders 55 for the packages or articles which are represented, and thus advertising of a very

forceful nature is obtained. The child asks for a package of a particular kind of goods in order to fill its shelf with goods.

I shall now describe in detail, in connection with the accompanying drawings, one embodiment in which my invention may appear.

In the drawings,

Fig. 1 is a front elevation of a structure embodying my invention;

Fig. 2 is a side elevation viewed from the left of Fig. 1;

Fig. 3 is a perspective view of the structure shown in Figs. 1 and 2;

Fig. 4 is a fragmentary detail view showing the interior of the structure;

Fig. 5 is a fragmentary view of opposite walls of the structure showing the counter and the silhouette mechanism;

Fig. 6 is a horizontal cross-section taken at the level of the counter shown in Fig. 5;

Fig. 7 is a fragmentary detail view showing the manner in which the side walls of the structure are secured together;

Fig. 8 is an elevational view of the same structure;

Fig. 9 is an interior view of the left-hand wall of Fig. 1. This view is taken on the line 9—9 of Fig. 10; and,

Fig. 10 is a horizontal cross-section taken above the level of the shelves on the interior of the house.

The structure shown in the figures consists essentially of front and rear walls 1 and 2, respectively, and side walls 3 and 4, and a roof comprising two parts 5 and 6.

The front wall 1 is provided with a door 7, through which access may be had to the interior of the structure. The wall is built 95 up of frame-members and panel-members, as is clearly shown in Fig. 6. The side frame-members 8 and the door frame-members 9 are channeled, as clearly shown in Fig. 6, and panels 10 upon which the pictorial representations are made, are secured in the channels of the frame-members 8 and 9. The frame-members 8 and 9 are secured together at the top and bottom by suitable rail-members 11 and 12, which are also 100 grooved to receive the edges of the lithographed board 10, which may be of thin wood, paper-board or other material. The top rail 11 may be of greater width, if desired, so as to provide suitable means for engaging the roof-members 5 and 6 to secure 105 the roof and the walls together. The rear

wall 2 is constructed in a manner similar to the front wall, with the side frame-members 8, a central frame-member 13, and top and bottom rails 11 and 12, respectively.

5 The side walls 3 and 4 are made up in a similar manner.

The side wall 3 is provided with an opening 14, which serves both as a window for admitting light and as a delivery window.

10 A roller curtain 15 is mounted at the top of the window; this curtain is preferably marked to represent an awning and may be extended at an angle and propped outwardly as shown in the dotted lines in 15 Fig. 1.

The rails 11 on the front and back walls are provided with gable portions 16 and 17, which may be formed integral with the rails or may be secured thereto.

20 The walls are secured together by means of angle-braces 18, shown more clearly in Figs. 7 and 8. Sockets 19, which may consist of small metal straps, are secured to the frame-members 8 at a suitable distance from the edges, so that the projecting prongs 20 of the angle-member 18 will fit into said sockets and hold the sides in proper position.

30 The side wall 3 is provided upon the interior thereof, adjacent the opening 14, with a shelf or counter 21, which may be secured in any suitable manner to the wall so as to afford a suitable counter over which the proprietor of the toy grocery may transact business with his customers. The counter 21 is slotted, as shown at 22, in order to provide a suitable mounting for cutouts 23, the shadows or silhouettes of which may be cast upon a thin, transparent curtain 24, mounted on a spring-roller 25 upon the inside of the wall 3. A shelf 26 may be mounted upon the opposite wall 4 so as to provide a suitable support for a projecting lantern or lamp 27.

45 Upon the interior of the house shelves, such as 28, 29, 30 and 31, are provided, so that the proprietor can place thereupon his stock of goods. Upon the wall back of the shelves are pictured articles or packages of goods which it is desired to advertise (see Fig. 4). These images, such as 30', 31', 32 and 33, may be photolithographed upon the walls or presented in any other suitable manner. Proper shelf room is provided in front of the pictures of the articles, so that the child may mount the articles themselves in front of the pictorial representations, the article covering and obscuring the picture.

60 These pictures furnish powerful suggestions, and the child will insist upon its elders securing the articles corresponding to the pictures, so that it may obtain the empty cartons for placing upon the shelves.

The roof-members 5 and 6 are provided 65 with notches, as shown at 34, which slip

over the rail-members 11, thereby holding the roof and the walls securely together. The members 5 and 6 may be hinged together, as by means of flexible tape or other convenient arrangement, said members consisting preferably of paper-board, thin wooden board, or the like.

It will now be apparent that I have provided a structure of very great utility in presenting advertising matter in a very 75 forcible manner to the consumer. The manufacturing company which desires to have its product advertised pays for a given amount of space and the toy house is put out by the advertising manager with a certain number of products advertised. The toy house is put in the hands of the child, who begins collecting the cartons or empty packages of the articles which are advertised, and places the same upon the shelf 85 in front of the pictorial representations of the articles. If the child's elders do not regularly purchase one of the articles so that the child may obtain a package or carton, the child will insist upon the elder securing that particular commodity, so that it may employ the carton—or even the article itself—in its toy house.

While I am aware that it is customary to label shelves for the reception of articles, I 95 wish it to be understood that the idea of providing images back of a position on a shelf, or the like, which images are adapted to be obscured or obliterated by placing the original article upon the space designated, 100 is entirely new in this connection.

While I have shown one particular embodiment of my invention, I do not intend to be limited to the precise details shown, but intend to employ such modifications 105 and equivalents as will suggest themselves to those skilled in the art.

What I claim as new and desire to protect by Letters Patent of the United States is:

1. In a device of the class described, a wall having thereupon a full sized facsimile representation or picture of an article of commerce and means for supporting directly in front of said picture the article there pictured, said article being adapted when brought in register with the picture to obscure the picture.

2. A structure for advertising purposes comprising a wall having a plurality of objects pictured thereupon, a shelf projecting from said wall and adapted to contain the objects pictured on the wall, such articles or objects being adapted to be placed upon the shelf so as to obscure the corresponding 115 picture.

3. A structure for the purpose described comprising a frame, panels in said frame for forming a closed structure, said panels having a plurality of articles or objects pic- 120 125 130

tured thereupon, a shelf secured to said frame just below said pictures, said shelf adapted to receive the originals of the objects pictured, said pictures being of such 5 size and so located with respect to the shelf that the same are obscured by the article being placed in front of them.

4. In a structure of the class described, a plurality of walls, a roof having notches for 10 embracing the outer corners of two of said walls, and means independent of the roof for securing said two walls to two other walls to form a complete inclosure.

5. In a structure of the class described, a plurality of substantially rectangular walls, 15 a pair of said walls having gables of less width than the walls, a roof comprising two portions connected together and each having notches for engaging the outer top

corners of the end walls adjacent the gables, 20 and angle-braces in the corners between walls for holding the walls together and for forming a complete inclosure.

6. In combination, a plurality of walls comprising wooden frames and paper 25 panels, a door in one of said walls, a window in another of said walls, a shelf on one of said walls, said shelf being secured to one of said frames, one of said paper panels having pictorial representations of objects 30 thereupon back of said shelf, said pictures being adapted to be completely obscured by placing the article itself upon said shelf in register with the picture.

In witness whereof, I hereunto subscribe 35 my name this 1st day of June, A. D. 1915.

WILLIAM PENTE.
